4 Claims. (Cl. 90—11)

The present invention relates to a process for machining tubular elements for heat exchangers of the type wherein the external surface which is in contact with a flow of cooling fluid is provided with fins, and especially for the fabrication of fuel element cans for nuclear reactors.

The invention is more especially concerned among cans of this type with those which are provided with adjacent rows of oblique and parallel fins forming a herringbone pattern, that is to say in which the fins of each row are inclined to the axis of the can and have an opposite angle of slant with respect to the fins of each adjacent row, said cans having preferably a circular transverse cross-section.

In accordance with this arrangement which is known per se, the fins induce convection currents in the flow and these latter periodically renew the fluid which is in contact with the can, especially within each unitary groove or channel which is formed between two successive fins.

The convection currents thus formed have a generally spiral flow pattern and are substantially symmetrical. The said currents are distributed around the can and follow vortical flow paths which are oriented in independent streams, thereby providing an appreciable improvement in the heat transfer coefficient.

However, the intensity of heat extraction is dependent on the number of recycling processes and on the rate of flow between the fins, and increases with the angle at which the fins are inclined to the longitudinal axis of the can. This angle of inclination, which can advantageously be increased to 45° and over, is nevertheless limited by the pressure loss within the flow and by the aerodynamic stresses which are liable to accelerate the processes of heat distortion of the fins.

Experimental research has revealed that the above-mentioned pressure losses and stresses are localized at the leading edges of the fins of each row. It is consequently an advantage to endow said fins with a curved shape with a mean inclination to the axis which increases from the upstream end to the downstream end in the direction of flow of the fluid. However, the profile which is thus obtained in the case of fins of this type usually complicates the machining thereof. The primary object of the present invention is to define an effective configuration which can be achieved by means of a process which is both particularly simple and easy to carry into effect.

The process in accordance with the invention is accordingly characterized in that it consists in machining the fins of each row by means of milling-cutter teeth having the shape of the transverse cross-section of the unitary channels formed between two successive fins in a same row, the said teeth being parallel to each other and grouped together in such a manner as to form a hollow end-mill, the axis of which makes a constant angle with the axis of the tubular element.

As a preferable feature, the said constant angle is chosen in such manner that the fin surfaces are inclined towards the downstream end of the fluid flow which is in contact with the element. In addition, and in accordance with another characteristic feature of the process, the axis of the hollow end-mill does not intersect the axis of the tubular element and the distance between these two axes, that is to say the length of their common perpen-

dicular, is maintained constant at the time of successive machining of each parallel fin of a same row.

Provision is thus made for the formation, row by row, of curved fins arranged in a herringbone pattern and forming surfaces of revolution having circular director-lines and slightly slanting at the downstream end of the flow, thereby making it possible in particular to free the milling-cutter teeth on completion of each successive pass which forms the fins in unitary sequence.

Further characteristic features and advantages of the process considered will become apparent from the following description of a number of examples of practical operation of the said process which are given by way of indication and not in any limiting sense.

15 In the accompanying drawings:

FIGS. 1, 2 and 3 are partial views showing fins which have been machined in a tubular element or nuclear fuel can, said fins being shown respectively in cross-section in a plane at right angles to the axis of the can (FIG. 1), in perspective (FIG. 2) and in projection on a plane passing through the axis of the can (FIG. 3).

20 FIG. 4 represents diagrammatically a perspective view of a can and of a hollow end-mill which serves to form curved fins in accordance with the process which is contemplated.

25 FIGS. 5 and 6 are respectively views in perspective and in projection in a plane at right angles to the axis of the can which is illustrated in FIG. 4.

30 As appears from FIG. 1, the can body 1 is provided on its external surface with rows of parallel fins such as the fin 2 which are shown in cross-section in a plane at right angles to the longitudinal axis of the said can. The said fins 2 are formed by hollowing out in the thickness of the body 1 channels or grooves such as the groove 3 by means of a series of suitable milling-cutter teeth 4 which are mounted in such manner as to form a hollow end-mill F, one particular form of embodiment of which is illustrated in FIG. 4.

35 The said hollow end-mill, which is in itself of conventional type, comprises a number of teeth 4 which are parallel to each other and inserted at intervals in a circular ring or annulus F1. Each tooth or bit 4 is made integral with the ring whereas this latter is mounted to rotate about the axis A—A' of the end-mill; the different mechanical components which produce the rotary motion of the end-mill have been omitted from the drawings.

40 In accordance with an essential characteristic feature of the machining process under consideration, the end-mill F cuts the can 1 in a given direction which is defined by the angle β which is made between the axis A—A' of the end-mill and the axis X—X' of the can, said angle being maintained constant at the time of machining of all the successive fins of a same row on the external surface of the can 1.

45 As can also be seen from FIGS. 1 and 4, the tips of the milling-cutter teeth 4 move in a circle having a radius which is equal to that of the ring F1, said circle being projected at right angles on the plane of FIG. 1 in an ellipse B. The profiles of the channels 3 between the fins 2 accordingly widen progressively as shown, for example, by the channels 3 and 3a of FIG. 1. Similarly, a slight increase both in the height and depth of said fins takes place progressively as the milling-cutter moves forward.

50 As will also be apparent from the figures mentioned above, the axis A—A' of the end-mill is displaced relatively to the center of the circular rod 5 which is surrounded by the can 1 and which consequently does not intersect the axis X—X' of this latter. The distance d 55 between these two axes which measures the length of their common perpendicular thus defines the angle β which is made between the axes A—A' and X—X' and

the exact position of the end-mill F with respect to the can 1 for the purpose of machining fins in any row, the transition from one fin to the next being carried out by means of a single movement of translation of the milling-cutter as a whole in a direction parallel to that of the axis X—X'. Similarly, the transition from one row of fins to the adjacent row for the purpose of forming a herringbone pattern is brought about by tilting the axis A—A' of the end-mill so as to give this latter a position which is symmetrical with that which it had previously occupied with respect to the plane which passes through the axis X—X' of the can and through the generator-line of this latter which separates the two rows of fins considered.

By reason of the angle of slant of the end-mill, that is to say of the angle β which is chosen for the purpose of cutting the can 1 with the end-mill teeth 4, the edges of the fins 2 are also projected in curves which are similar to ellipses as can be seen from the external view which is illustrated in FIG. 2. The flow lines which are followed by the cooling fluid have a pattern which is shown diagrammatically by the arrow C. The machining of the curved fins having circular director-lines endow said fins with a configuration in the form of rounded herringbones with a slight slant at the point of admission of the fluid into the unitary channels formed between two successive fins and a distinctly sharper angle of slant at the exit. By way of example, this angle of slant with respect to the longitudinal axis of the can can be comprised between 15° and 30° at the fin-channel entry and between 40° and 70° at the fin-channel exit.

The longitudinal cross-section of FIG. 3 additionally shows the angle of inclination of the fins which is necessary in order to permit the end-mill teeth to pass without incurring any danger of cutting into other fins. As a preferable arrangement, the angle γ of inclination of the axis A—A' relatively to a direction N—N' which is normal to the axis of the element (namely the complement of the angle β which has been defined earlier) must be at least equal to 10° in the direction which tends to incline the fin surfaces towards the downstream end of the fluid flow. This angle of inclination in fact permits the possibility of achieving a better discharge of fluid from the fin channels 3 along the flow lines which are shown diagrammatically by the arrow C. On the other hand, the said angle of inclination must not be greater than 30° in order that the depth of the fin channels should not be made excessive when the fins are of suitable height.

The diagrammatic FIGURE 5 is a view in elevation of the can which is illustrated in FIG. 4 and shows partially two rows of symmetrical curved fins 2, corresponding to the transverse cross-section which is shown in FIG. 6.

In FIG. 6, the fuel rod 5 is shown in its entirety as surrounded by its can 1, the fins 2 of this latter being separated by longitudinal grooves 7 and 8 forming recesses which are necessary for the purpose of freeing the teeth of the end-mill F and which also facilitate the admission of fluid within the fin channels 3 and the discharge of said fluid from these latter. Longitudinal partition walls 9 can also be advantageously provided between said grooves so as to center the can with respect to a structure (which has not been shown in the drawings) which surrounds said can and especially within the fuel channel of a nuclear reactor.

Finally the ellipse B which is shown in projection on the plane of FIG. 6 shows in a more precise manner the circular path which is followed by the tips of the end-mill teeth. A study of this configuration reveals that the overthickness of metal and the recessed portions around the can are limited to reasonable values when said recessed portions are open in a V-shape and occupy approximately one half the height of the fins. This height is usually chosen so as to be greater at the fluid exit end in order to provide more effective interdependence between said height and the circular configuration of the channels. The external contour of the fins is determined by a circle or by a polygon, the shape of which can be produced directly by extrusion of a blank in which the recesses for the admission and discharge of fluid are formed in the manufacturing process and which is then employed as starting material for the machining of fins according to the arrangements which have been set forth hereinabove.

It will be understood that the invention is not limited in any sense to the form of embodiment which has been described and illustrated and which has been given solely by way of example. In particular, the configuration of the fins in accordance with the process of the invention could give rise to shapes and dimensions which can be variable as a function of the number of rows of fins. In a general manner, the optimum dimensions of the fin channels are of the order of one millimeter in width and one centimeter in depth. The thickness of each fin is also of the same order of magnitude as the width of each channel but can decrease to a more or less marked extent towards the tips of the fins.

What I claim is:

1. Process for machining adjacent rows of parallel fins in the external surface of a tubular element which is in contact with a fluid flow, wherein said fins are inclined to the axis of said tubular element and have an opposite angle of inclination from one row to the next so as to form herringbone configurations, characterized in that said process consists in machining the fins of each row by means of milling tools having the shape of the transverse cross-section of the unitary channels which are formed between two successive fins in a same row, said milling tools being parallel to each other and grouped together in such a manner as to form a circular hollow end-mill having an axis which makes a constant angle with the axis of said tubular element.

2. Process in accordance with claim 1, characterized in that said constant angle is so determined that said fins are inclined towards the downstream end of said fluid flow.

3. Process in accordance with claim 2, characterized in that said constant angle is comprised between 60° and 80° .

4. Process in accordance with claim 1, characterized in that the axis of said hollow end-mill is displaced with respect to the axis of said tubular element.
